WRAPAROUND GARMENT COVER

Don Holliday, Harrison, Ark.

Application August 10, 1954, Serial No. 448,802

5 Claims. (Cl. 223—98)

This invention relates to garment covers.

It is an object of the present invention to provide a cover for garments particularly useful when the garments are delivered by dry cleaning establishments, department stores and manufacturers.

It is another object of the present invention to provide a garment cover for garments suspended on hangers which may be easily and readily removed from the garments without a special rack or other equipment and as easily placed thereon.

It is still another object of the present invention to provide a garment cover of the above type which may be returned to the store for unlimited repeat use, thereby eliminating the conventional paper bag cover which cannot be used more than once.

It is still another object of the present invention to provide a garment cover of the above type which will not absorb moisture from the air while protecting the garment from rain, dust or the like and which, considering the prolonged life of the cover, is cheaper to employ than conventional paper bags.

Other objects of the present invention are to provide a garment cover bearing the above objects in mind which is of simple construction, inexpensive to manufacture, has a minimum number of parts, is easy to use and efficient in operation.

For other objects and a better understanding of the invention, reference may be had to the following detailed description taken in connection with the accompanying drawing, in which:

Figure 1 is a front elevational view of the garment cover embodying the features of the present invention and shown in operative use on a hanger;

Fig. 2 is a view similar to Fig. 1 of a modified form of the present invention; and

Fig. 3 is a fragmentary enlarged sectional view taken along the line 3—3 of Fig. 1.

Referring now more in detail to the figures, 10 indicates generally a wire hanger for garments including the usual hook 11, the neck portion 12, upper shoulder portions 13 and the sloping lower shoulder portions 14 connected at their lower ends by the transverse trouser or skirt supporting portion 15.

A flexible waterproof cover indicated generally at 16 is provided and includes a rear wall 17 having the upper edge thereof following the contour of the upper and lower shoulder portions 13, 14 of hanger 10, substantially as illustrated. The rear wall 17 along one sloping edge 18 is secured to a front wall 19 by means of the stitching 20, the front wall 19 being integral with the rear wall 17, along the vertical fold line 20'.

The opposite sloping upper edge of the front wall 19 above the other shoulder portion 14 is secured to an intermediate wall 21 by means of stitching 22 (Fig. 3), the other vertical edge of the front wall 19 being integral with the intermediate wall 21 along a vertical fold line 22'. The intermediate wall 21 is disposed intermediate

2

the front wall 19 and rear wall 17 and terminates at 23' (Fig. 1) thus extending across only one half the width of the cover.

It will be noted that the righthand half of the cover 5 is supported on the shoulder portion 14 of hanger 10 by means of the stitching 20, while the lefthand portion 14 of the hanger is disposed below the stitching 22 to support the other half of the cover. The stitching 22, of course, terminates short of the stitching 20 providing a 10 space between the front and rear horizontal upper edges of the cover through which passes the neck 12 and hook 11. It will also be noted that the lefthand portion of the rear wall 17 overlaps the intermediate wall 21.

The flap 23 is secured to the sloping portion of rear 15 wall 17 by means of stitching 24, the stitching 22, hanger 10 and the front and intermediate walls 19 and 21 being received between the flap 23 and the rear wall 17 (Fig. 3).

Thus, a garment, not shown, supported on the hanger 20 10 will be entirely protected from moisture, dirt or the like with the flap 23 holding the cover about the garment in the manner shown. It will also be noted that no special rack or equipment is necessary for putting the cover 10 on the garment and hanger and that the cover may easily be removed with only one hand. The cover 25 is, of course, entirely open at the bottom. The covers may be made in two sizes, one for suits or the like and the other for dresses and long coats.

To remove the cover, the flap 23 is removed rearwardly 30 while lifting it off the shoulder portion 14 and is then folded back. The cover is then lifted completely free of the hanger. It can, of course, be returned by reversing the above operations.

Referring now particularly to Fig. 2 there is shown a modified form of the present invention wherein the 35 front and rear walls of the cover, 19a, 17a, are elongated at their left sides, substantially as illustrated. The left hand edge of the front wall 19a slopes downwardly and outwardly and is integral therealong with the intermediate flap 21a along the tapered fold line 22a. The intermediate flap 21a again terminates along the vertical edge 23b, while the righthand shoulder portion of the front wall 19a is secured to the rear wall 17a by the stitching 20a. In this form, a parallelogram-shaped flap 23a is secured to the rear wall 17a by means of the stitching 45 24a. In other respects the form of the invention shown in Fig. 1 and Fig. 3 is the same as that shown in Fig. 2, and like reference numerals identify like parts throughout the several views.

While various changes may be made in the detail 50 construction, it shall be understood that such changes shall be within the spirit and scope of the present invention as defined by the appended claims.

What I claim as new and desire to protect by Letters Patent of the United States is:

- 55 1. A garment cover for a garment hanger and garment thereon, said cover comprising front and rear walls, each wall having a pair of shoulder portions, a horizontal upper edge and a pair of vertical edges and adapted to fit downwardly over the garment and hanger, said front and rear walls being secured together along one shoulder portion, said front and rear walls being open across the horizontal upper edges thereof whereby to receive the hanger hook upwardly therethrough, said front and rear walls being integral along the vertical edges adjacent said shoulder portions which are secured together, the other vertical edges of said front and rear walls being separable, an intermediate wall integral with said other vertical edge of said front wall and disposed intermediate said front and rear walls and having a sloping shoulder portion, said intermediate and front walls being secured together along the adjacent shoulder portions, and means
- 60
- 65
- 70

for engaging the other shoulder portion of said rear wall with said front wall whereby to retain the cover about the garment and hanger.

2. A garment cover according to claim 1, said intermediate wall having a free vertical edge terminating substantially midway between the vertical edges of said front wall, below the hook portion of the hanger.

3. A garment cover according to claim 2, said means for engaging said other shoulder portion of said rear wall with said front wall comprising a flap, said flap being secured to the shoulder portion of said rear wall.

4. A garment cover according to claim 3, the side

of said cover having said flap being elongated, the vertical edge connecting said intermediate wall with said front wall being inclined downwardly and outwardly, said flap being substantially parallelogram-shaped.

5. A garment cover according to claim 3, said front and rear walls, intermediate wall and flap being formed of flexible waterproof material.
